UNITED STATES PATENT OFFICE

JAMES H. AVERY, OF FRANKLIN, MASSACHUSETTS, ASSIGNOR TO NATIONAL RING TRAVELER CO., OF PROVIDENCE, RHODE ISLAND, A CORPORATION OF RHODE ISLAND

TWISTER RING AND TRAVELER

Application filed May 11, 1927. Serial No. 190,594.

The twister traveler as at present constructed is a compromise between two factors of opposite tendency, one the necessity of having sufficient surface friction between the 5 traveler and the ring to cause the traveler to drag and thereby impart twist to the yarn, and the other the natural tendency to relieve the friction as much as possible.

In the earliest form of twister traveler, the 10 necessity for the traveler to act as a drag and thereby impart twist to the yarn was not perceived and the traveler was made practically no friction surface between its flanges.

The first real improvement in the twister 15 traveler came when the so-called "broken back" traveler was brought out many years ago. In this type of traveler, the back of the traveler was bent to provide a friction surface adapted to bear on the ring between the 20 traveler flanges and thereby cause the traveler to act as a drag. With the advent of the broken back traveler, however, friction became a definite factor and lubrication to relieve such friction to some extent became 25 necessary, the customary practice being simply to smear the inner face of the twister ring with a lubricant which would melt under the heat generated by the traveler running on the ring and would flow down to the traveler 30 foot where the wear was greatest and the need of lubrication most pronounced.

This method of lubrication, however, had 35 its disadvantages, and within recent years Mr. Philip C. Wentworth devised and patented a twister traveler in which the traveler itself was provided with a lubricant pocket on the outer face of its back, so as automatically to lubricate itself. (Wentworth Patent No. 1,415,072, dated May 9, 1922.)

40 The design of the broken back traveler, either with or without the Wentworth lubricant pocket, is followed today and such travelers therefore may be considered as heretofore standard in the art. The difficulty with this traveler, however, is that it is somewhat top heavy in action and does not ride the ring in true balance. This is due to the fact that the traveler, in acting as a drag, tends to tip 45 forwardly in the direction of rotation so 50 that the traveler foot is drawn up against the

bottom edge of the ring and soon develops wear.

I have discovered that this wear can be reduced, thereby materially prolonging the life of the traveler, while at the same time 55 avoiding the tendency of the traveler to tilt forwardly in the direction of rotation and thus ride the ring out of balance.

My invention is a departure from conventional design in both ring and traveler, but 60 such departure results in a better balancing of the traveler while running on the ring and a reduction in the wear at the traveler foot, without, however, lessening the twist imparted to the yarn by the traveler. 65

According to my invention, the twister ring is so designed as to present a surface of greater thickness at its bottom than at its top edge, the bottom being rounded in the arc of a true circle and the inside face of the ring being 70 beveled on about a 10° angle from top to bottom so as to present an inclined plane or cam face. The traveler is correspondingly changed, being curved on a larger arc at its foot, so as to provide a preponderance of 75 weight at the foot, and having its back inclined to correspond to the inclination of the inside face of the ring. 80

As a result of these departures in traveler and ring construction, the preponderance of 85 traveler weight is at the bottom or foot of the traveler, that is to say, the center of gravity of the traveler is lowered so that the traveler rides the ring in better balance, standing more nearly vertical thereon and not being 85 top heavy, thus reducing wear and prolonging the life of the traveler, and the design of the ring is such as to cooperate towards the attainment of these desiderata.

While not committed to any exact theory, 90 it would seem that this action is due to the fact that in the run of the traveler, the correspondingly inclined faces of the ring and traveler back act as a cam to lift the traveler vertically in a plane which is the resultant of 95 the centrifugal force tending to throw the traveler horizontally off the ring and the upward lifting action of the inclined plane or cam surface thus provided by the upwardly beveled face of the ring and traveler. 100

In my theory of this action, the tendency of the traveler to lift vertically in a plane which is the resultant of these two counteracting forces is offset by the preponderance of weight at the foot of the traveler, so that in theory at least, the one equalizes the other, resulting in the traveler riding the ring in theoretically perfect balance.

As illustrative of my invention, I show in 10 the accompanying drawings a form of traveler and ring which I have found satisfactory under actual conditions of use. In these drawings:

Fig. 1 is a section of a twister ring in accordance with my invention, equipped with a twister traveler in accordance with my invention, and

Fig. 2 is an enlarged diagrammatic view in which I have attempted to illustrate the theory of my invention.

The ring R conforms to accepted twister ring design except that my ring is of greater thickness at its bottom edge than at its top, as indicated at 1, the bottom being curved on 25 the arc of a true circle, and the inner face of the ring being beveled at approximately a 10° angle from top to bottom, resulting in an inclined cam or bearing face 2 of upward lifting tendency.

Similarly, my twister traveler follows generally accepted traveler design, except that it also is of greater thickness at the bottom than at the top, as indicated at 3, and has its back beveled as at 4 on an incline corresponding to 35 the inclination of the bearing face 2 of the ring. This results in a traveler in which there is a preponderance of weight at the bottom or foot, and hence a lower center of gravity than the old style top heavy broken 40 back traveler.

I have attempted diagrammatically to illustrate the action of my improved traveler and ring in Fig. 2, wherein the line C F indicates the lines of centrifugal force; the line 45 L the line of lifting action of the traveler, due to the fact that the beveled bearing faces of the ring and traveler present an inclined plane along which the traveler tends to ride upwardly; and the line r the resultant of 50 these two counteracting forces C F and L. The resultant r represents therefore the theoretical upward lift of the traveler which may be assumed to be the vertical axis of the traveler. By reason, however, of the pre- 55 ponderance of weight at the foot of the traveler, indicated at W, and representing the gravity pull of the traveler in a direction opposite to its upward lifting tendency r, the counteracting forces r and W theoretical- 60 ly, at least, will counterbalance each other so that the traveler will ride in perfect balance on the ring, assuming and maintaining a position which is vertical and in which the upper flange of the traveler is wholly free of 65 the upper edge of the ring and its lower

flange or foot is in true bearing on the lower edge of the ring, thereby relieving wear at the traveler foot.

As I have stated hereinbefore, I do not wish to be confined to any exact theory of operation. Results, however, are apparent and demonstrable, and these results show a marked improvement in the balancing of the traveler, with corresponding diminution in wear on both traveler and ring.

While applicable to either the old style traveler without the Wentworth lubricant pocket or to the Wentworth self-lubricating traveler, I have purposely shown my invention as applied to the Wentworth type traveler in which a lubricant pocket 5 is formed in the traveler back.

Various modifications in the design of both ring and traveler may obviously be made within the spirit and scope of my invention as defined by the appended claims.

What I therefore claim and desire to secure by Letters Patent is:—

1. In combination, a twister ring and a traveler thereon, each having cooperating inclined bearing surfaces disposed to give an upward resultant from the outward centrifugal tendency of the traveler in rotation.

2. In combination, a twister ring and a traveler thereon, each having cooperating inclined bearing surfaces disposed to give an upward resultant from the outward centrifugal tendency of the traveler in rotation, the lower edge of the ring being curved on a radius greater than that of its upper edge and the lower edge of the traveler being similarly curved to correspond to the lower edge of the ring and presenting a preponderance of weight below its center.

3. In combination, a twister ring and a traveler thereon, each having cooperating inclined bearing surfaces disposed to give an upward resultant from the outward centrifugal tendency of the traveler in rotation, there being a preponderance of weight at the traveler foot and such preponderance substantially counterbalancing the upward lifting action of the traveler.

4. In combination, a twister ring having an inclined bearing surface on its inner face and a traveler having a correspondingly inclined bearing face cooperating therewith.

5. In combination, a twister ring having an inclined bearing surface on its inner face and a traveler having a correspondingly inclined bearing face cooperating therewith, the lower edge of the ring being curved on a radius greater than that of its upper edge and the lower edge of the traveler being similarly curved to correspond to the lower edge of the ring and presenting a preponderance of weight below its center.

6. A vertical twister ring having a bearing face of upward flare to impart an upward lifting effect to a traveler riding on said ring

and having a correspondingly flared bearing face.

7. A vertical twister ring having on its inner face a conic bearing surface of upward flare effective to impart an upward lifting effect to a traveler riding on said ring and having a correspondingly shaped bearing face.

8. A vertical twister ring having a beveled inner face of upward flare effective to impart an upward lifting effect to a traveler riding on said ring and having a correspondingly beveled bearing face.

9. A vertical twister ring having a beveled inner face of upward flare and a rounded lower edge of greater radius than its upper edge and effective to impart an upward lifting effect to a traveler riding on said ring and having its bearing face correspondingly shaped and its lower edge correspondingly curved.

10. A vertical twister ring having a rounded lower edge of greater radius than its upper edge and adapted to support a traveler having its lower edge correspondingly curved.

11. A vertical twister ring thicker at its bottom edge than at its top edge and adapted to support a traveler having its lower edge correspondingly thickened.

12. A vertical twister ring thicker at its bottom edge than at its top edge and having its inner face beveled between said edges to provide a bearing surface of upward flare effective to impart an upward lifting effect to a traveler riding on said ring and having its bottom edge correspondingly thickened and its bearing face correspondingly shaped.

13. A twister traveler for use on a vertical twister ring having an upwardly inclined bearing surface and a rounded lower edge of greater radius than its upper edge, consisting of a member having a correspondingly inclined bearing surface and having its lower horn correspondingly curved on a greater radius than its upper horn.

14. A twister traveler for use on a vertical ring having an upwardly inclined bearing surface and a rounded lower edge of greater radius than its upper edge, consisting of a member having a correspondingly inclined bearing surface and having its lower horn correspondingly curved on a greater radius than its upper horn to present an excess of weight below the longitudinal center thereof.

15. A twister traveler for use on a vertical twister ring having an upwardly inclined bearing face to impart an upward lifting effect to the traveler, consisting of a member having a correspondingly inclined bearing face.

16. A twister traveler for use on a vertical twister ring having a bearing face shaped to provide a bearing surface of outward flare effective to impart an upward lifting to the traveler, consisting of a member having its

back formed to provide a correspondingly shaped bearing surface of outward flare.

17. A twister traveler for use on a vertical twister ring having a bearing face shaped to provide an upwardly inclined bearing surface effective to impart an upward lifting effect to the traveler, consisting of a member having a portion of its back formed to provide a correspondingly inclined bearing surface.

18. A twister traveler for use on a vertical twister ring having a bearing face shaped to provide an upwardly inclined bearing surface and having a rounded lower edge of greater radius than its upper edge and effective to impart an upward lifting effect to the traveler, consisting of a member having a portion of its back formed to provide a correspondingly inclined bearing surface and having its lower horn correspondingly curved on a greater radius than its upper horn.

19. A twister traveler for use on a vertical twister ring having a bearing face shaped to provide an upwardly inclined bearing surface effective to impart an upward lifting effect to the traveler, consisting of a member having a portion of its back bent to provide a correspondingly inclined bearing surface and having its lower horn curved on a greater radius than its upper horn to present an excess of weight below the longitudinal center thereof.

In testimony whereof I affix my signature.
